CLAIM

The ornamental design for a combined multi-purpose slicer and juicer with interchangeable accessories, as shown and described.

DESCRIPTION

FIG. 1 is a perspective view of a combined multi-purpose slicer and juicer with interchangeable accessories, including interchangeable accessories, showing my new design; FIG. 2 is a perspective view of the combined multi-purpose slicer and juicer with interchangeable accessories showing one of the interchangeable accessories;

FIG. 3 is a side elevational view with the opposite side being a mirror image thereof;

FIG. 4 is a front elevational view thereof;

FIG. 5 is a rear elevational view thereof;

FIG. 6 is a top plan view thereof; and,

FIG. 7 is a bottom plan view thereof.

The portions shown in broken lines are included for illustrative purposes only and form no part of the claimed design.
